METHOD OF MANUFACTURING PAPER SIP STRAW

Filed March 12, 1931

FIG. 1.

FIG. 2.

Inventor
Karl E. Garling

By his Attorney

Edmund

UNITED STATES PATENT OFFICE

KARL E. GARLING, OF NEWARK, NEW JERSEY

METHOD OF MANUFACTURING PAPER SIP-STRAWS

Application filed March 12, 1931. Serial No. 521,908.

Among the principal objects which the present invention has in view are: to impart a distinctive characteristic feature to the straws; to accentuate a structural feature of the straws; to form a natural spiral line running throughout the completed straws; and to simplify the method for imparting to the product the spiral line above referred to.

Drawings

Figure 1 is a side view of a roll of paper strip, the side of which has been treated to color the edge of the strip.

Figure 2 is a pictorial view showing a sip-straw constructed and arranged in accordance with the present invention, and as resulting from the method herein disclosed, a portion of the paper strips composing the straw is shown in separated relation.

Description

The present invention relates particularly to paper sip-straws such as are disclosed in an application for patent filed by me under date of December 5, 1930, the serial number of which is 500,157, and consists principally in preparing and employing paper strips pre-treated to impart to the finished product a spiral line such as indicated by the numeral 7 in Figure 2 of the drawings.

As disclosed, straws manufactured in accordance with the present invention are constructed of two separate strips of paper indicated in the present drawings by the numerals 8 and 9. These strips are of even width and are so disposed that the edges of the outer strip are approximately disposed at the median line of the inner strip 8. The edges of the outer strip 9 are tinted or colored as indicated at 10 in Figure 2. In this figure, one only of the edges is shown as tinted, but it will be understood that both edges may be tinted, in which case the line 7 would be intensified or broadened.

As shown in Figure 1, the strip 9 is tinted

or colored while rolled on the spool 11. Subsequently, this strip 9 is provided with adhesive 12 which causes the strip 9 to adhere to the strip 8 when overlaid thereon.

When, now, in the process of manufacture, the strips 8 and 9 are handled to form the sip-straw by being spirally wrapped in superposed relation on a suitable mandrel or implement, the tinted edge or edges of the strip 9 will show throughout the length of the straw as seen at the left of Figure 2 of the drawings.

It will be understood that any suitable color for tinting the edge or edges of the strip 9 may be used. Also it will be understood that if desired, one edge of the said strip may have one color and the opposite edge another color, which combining in the finished product, would give varied and pleasing effects.

Claims:

1. The method of making paper sip-straws by spirally wrapping paper strips in superposed relation, coloring the outermost strip prior to wrapping it so that the colored portion forms a visible spiral area on the completed sip-straws, and adhesively uniting said strips.

2. The method of making paper sip-straws by spirally wrapping paper strips in superposed relation, coloring the edge of the outermost strip prior to wrapping it so that the colored edge portion forms a visible spiral line on the completed sip-straw, and adhesively uniting said strips.

3. The method of making paper sip-straws by spirally wrapping paper strips in superposed relation, coloring the edge portions of the outermost strip prior to wrapping it so that the colored edge portions form visible spiral areas on the completed sip-straws, and adhesively uniting said strips.

4. The method of making paper sip-straws by spirally wrapping paper strips in superposed relation, coloring the edges of one of

said strips prior to wrapping it so that the colored portion forms a spiral area on the completed sip-straws, and adhesively uniting said strips.

- 5 5. The method of making paper sip-straws by spirally wrapping paper strips in super-posed relation, coloring one edge of said strips prior to wrapping it so that the colored portion forms a spiral area on the completed
10 sip-straws, and adhesively uniting said strips.
